BY *J. R. Connell.* Attest.

UNITED STATES PATENT OFFICE.

WILLIAM F. DONNELL, OF HEMATITE, MISSOURI.

MILK-CAN.

1,065,667.

Specification of Letters Patent. Patented June 24, 1913.

Application filed December 26, 1911. Serial No. 667,773.

To all whom it may concern:

Be it known that I, WILLIAM F. DONNELL, a citizen of the United States, residing at Hematite, Missouri, have invented a certain 5 new and useful Improvement in Milk-Cans, of which the following is a full, clear, and exact description, such as will enable others skilled in the art to which it appertains to make and use the same, reference being had 10 to the accompanying drawings, forming part of this specification, in which—

Figure 1 is a side elevational view of a milk can of my improved construction, parts thereof being broken away and the lower 15 portion being shown in vertical section. Fig. 2 is an enlarged detail section taken approximately on the line 2—2 of Fig. 1. Fig. 3 is a detail elevation of the upper portion of the can, and showing one of the hooks 20 used for attaching the cover to the body of the can. Fig. 4 is a vertical section taken on the line 4—4 of Fig. 3.

This invention relates generally to new 25 and useful improvements in cans particularly intended for containing milk during transportation and storage, although cans of my construction can be advantageously used for containing any liquid or semi-liquid products.

The principal object of my invention is, 30 to provide a can of simple construction which can be easily and cheaply manufactured, which can is constructed so as to be easily and quickly cleansed, and therefore 35 kept in a perfectly sanitary condition.

Further objects of my invention are: to 40 construct a can having a body portion formed of one piece of metal drawn to proper form, thereby doing away with the use of rivets and rivet holes in the formation 45 of the can body; to provide a cover for the body, and to arrange on said cover a gasket for the purpose of providing a perfect air and water-tight joint between the can body and cover when the latter is properly applied; to form the lower end of the body 50 of the can and the cover thereof so that cans can be readily nested when piled one on top of the other and to provide simple fastening means between the cover and body, 55 which can be manipulated so as to draw the cover into close engagement with the upper end of the body, thereby compressing the gasket equally at all points between the cover and the body, and consequently form-

ing an air and water-tight joint, which is a particularly desirable feature in large cans.

To the above purposes my invention consists in certain novel features of construction and arrangement of parts hereinafter 60 more fully described and claimed.

Referring by numerals to the accompanying drawings: 1 designates the body of the can which is preferably cylindrical and formed from a single piece of sheet metal drawn or pressed so as to form a seamless receptacle in the form of a cylinder having the same internal diameter throughout its length and with a perfectly smooth, unbroken interior surface.

The bottom 2 of the can is preferably 70 made convex, and that portion of the body of the can between the bottom 2 and the wall is rounded as designated by 3 in order that the lower end of one can will readily 75 adjust itself to the seat formed in the top or cover of an adjacent can when the cans are arranged one on top of the other during storage or while in transit.

The upper end of the body of the can is 80 provided with an annular bead 4, the same being preferably wired, as shown.

5 designates plates which are applied to the outer surface of the body of the can at diametrically opposite points, and formed 85 on the upper ends of these plates are hooks 6 adapted to be engaged by the cover-attaching means. Formed integral with the lower portions of the plates 5 are perforated ears 7 from which are suspended loops 8 which 90 perform the function of handles whereby the can can be readily lifted and carried. Formed integral with each plate 5 and preferably at a point between the ears 7 is a loop 9 which is adapted to cooperate with a portion 95 of the cover-attaching means herein-after described.

The plates 5 are preferably fused or 100 sweated onto the body of the can, thereby avoiding the use of rivets and the formation of rivet holes through the can body, and after said plates have been properly applied to the can body the entire structure is preferably plated or coated with suitable non-rusting material.

10 designates the can cover which is 105 preferably constructed of a single sheet of metal, with its edge 11 bent around a heavy wire 12 to form a marginal bead. That portion of the metal forming the cover immediately 110

adjacent to the bead which is bent upwardly as designated by 13 to form an annular rib which is substantially of inverted U-shape in cross section, thereby forming a seat for the bead 4 on the top of the can body when the cover is applied thereto. Arranged within this annular rib 13 is a gasket 14 of rubber or analogous material, which, when compressed under the downward pressure applied to the cover, forms an air and liquid-tight joint between the cover and the can body. The main body portion of the cover 10 occupies a plane substantially below the plane occupied by the top of the annular rib 13, and thus a shallow seat is formed in the central portion of the cover for the lower end of an adjacent can when the same are arranged one on top of the other during storage or transit (see dotted lines —a— Fig. 2).

Suspended from the wire 12 in the beaded edge of the cover 10 is a link 15, and pivotally carried by the lower end thereof is a hook 16, the lower end of which is adapted to engage either one of the hooks 6. Arranged on the edge of the cover 10 directly opposite from the link 15 and suspended from the wire 12 is a link 17, the lower end of which is bifurcated, and pivotally mounted therein is the bifurcated upper end of a lever 18. The lower end of this lever is provided with an opening 19 adapted to receive either one of the loops 9 when the cover is properly positioned and locked to the can body.

Pivotally carried upon a pin 20 that is seated in the upper portion of the bifurcated upper end of the lever 18 and in a plane above the pivot pins between the link 17 and lever 18, is a hook 21, the lower end of which is adapted to engage either one of the hooks 6.

I have described my improved can as being particularly intended for use in the shipment and storage of milk, but it will be readily understood that cans constructed substantially as herein shown and described can be advantageously utilized in the transportation of sea foods, such as fish, oysters and the like, and said can can be also used for the shipment of garbage or for any product which necessitates the use of an air and liquid-tight receptacle.

When the cover is applied to the can, the hook 16 is engaged beneath the hook 6 on one side of the can and the cover is now manipulated downward on to the upper end of the can body, with the upper portion of the bead 4 bearing against the under side of the gasket 14.

The lever 18 is now manipulated so that its lower end is uppermost, as shown by dotted lines in Fig. 2, and when so positioned the pivot pin 20 occupies a plane below the pivot pins between the link 17 and lever 18.

With the parts so positioned the lower end of the hook 21 can readily be engaged beneath the corresponding hook 16 and the lever 18 is now swung downwardly and in so doing the pivot pins 20 are moved into a position above the pivot pins between the link 17 and lever 18, thereby shortening the distance between the hook 6 and the edge of the cover, and, as a result, the cover is drawn downwardly with pressure onto the upper end of the can body, which action compresses the gasket 14, thereby forming an air and water-tight joint between the cover and can body.

The lower end of the lever 18 is moved into a position against the lower portion of the plate 5 with the loop 4 of said plate projecting through the opening 19, and the lever is locked into this position by the application of a sealing wire, or like device.

The body of the can is imperforate and seamless inasmuch as it is made from a single piece of sheet metal drawn to proper shape and the entire structure is entirely devoid of rivets or like fastening devices.

The can covers can be readily placed in or removed from position, and where a number of the cans are piled up for storage or for transportation, said cans can be readily nested, one on top of the other.

The body of the can is of the same diameter throughout its length, thereby facilitating the cleansing of the interior, and when said cans have been thoroughly washed they can be quickly dried and rendered sanitary by being placed in the open air in such positions that the sun's rays can enter the interior of the cans.

It will be understood that minor changes in the size, form and construction of the various parts of my improved can may be readily made and substituted for those herein shown and described without departing from the spirit of my invention, the scope of which is set forth in the appended claims.

I claim:

1. In a milk can, the combination with a seamless cylindrical receptacle formed of a single piece of sheet metal, said receptacle having the same internal diameter throughout its length, a bead on the upper edge of said receptacle, the lower end of the wall of which receptacle is rounded inwardly, of a detachable one piece cover for said cylindrical body, the central portion of which cover is depressed with respect to the edge thereof to form a seat for the lower rounded end of a superimposed can, which cover is provided adjacent to its edge with an annular groove adapted to receive the bead on the upper edge of the body of the can, a pair of hooks fixed to the body of the receptacle near the upper end thereof, a hook pivotally connected to the edge of the cover

and adapted to engage one of the hooks on the body of the receptacle, a link pivotally connected to the edge of the cover, a lever pivotally connected to said link, and a hook pivotally connected to said lever, which last mentioned hook is adapted to engage one of the hooks on the body of the receptacle to hold the cover thereon.

2. In a milk can, a seamless cylindrical body, hooks fixed to said body near its upper end and on opposite sides thereof, a cover provided adjacent to its edge with a groove which is of inverted U-shape in cross section and which receives the upper end of the wall 15 of the cylindrical receptacle when the cover is positioned thereon, a link pivotally connected to the edge of the cover, a hook pivotally connected to said link and adapted to engage one of the hooks on the body of 20 the receptacle, a second link pivotally connected to the edge of the cover, a lever pivotally connected to said second mentioned link, and a hook pivotally connected to said lever for engaging one of the hooks 25 on the body of the receptacle to lock the cover thereon.

3. In a milk can, the combination with a seamless cylindrical receptacle, of a pair

of plates fixed to said cylindrical receptacle on opposite sides thereof, hooks on the upper ends of said plates, which hooks are adapted to be engaged by the locking means carried by the cover for the receptacle, and a handle pivotally connected to the lower portion of each plate.

4. In a milk can, the combination with a seamless cylindrical body provided on its upper edge with a bead, of a removable cover for said body, which cover is provided adjacent to its edge with a groove 40 adapted to receive the bead on the upper edge of the body, a hook on the cylindrical body, a hook depending from the edge of the cover and adapted to engage the hook on the body, and a plurality of fastening 45 devices carried by the edge of the cover for engaging parts of the body of the can when said cover is applied thereto.

In testimony whereof I hereunto affix my signature in the presence of two witnesses, 50 this 20th day of December, 1911.

WILLIAM F. DONNELL.
